Per Lewis L. Coburn Atty.

United States Patent Office.

TYLER C. LORD, OF CHICAGO, ILLINOIS.

Letters Patent No. 95,363, dated September 28, 1869.

IMPROVED HINGE FOR BLINDS.

The Schedule referred to in these Letters Patent and making part of the same.

To all whom it may concern:

Be it known that I, TYLER C. LORD, of Chicago, in the county of Cook, and State of Illinois, have invented a new and useful "Improved Hinge for Window-Blinds;" and I do hereby declare the following to be a full, clear, and exact description of the same, reference being had to the accompanying drawings, and the letters and figures marked thereon, which form a part of this specification, and in which—

Figure 1 represents an inside view of the window-blind and casing to which the hinge is attached;

Figure 2, an outside view of the casing and blind, with the hinge attached;

Figure 3, a top view of the same;

Figure 4, a bottom view; and

Figure 5, an edge view.

The nature of my invention consists in constructing a window-blind hinge, with a circular plate, B, revolving on a central pin, D, and provided with cogs or teeth C on the under side thereof, and a cover or projecting rim, F, in combination with the bevel-wheel H and shaft I.

To enable those skilled in the art to understand how to manufacture and use my invention, I will describe the same with particularity.

The same letters of reference refer to the corresponding parts in the different figures.

In the annexed drawing—

A represents that part of the hinge that is attached to the window-blind; and

E, the part attached to the window-casing.

A consists, in part, of a large circular plate, B, on the under side of which, near its edge, there is a rack of teeth or cogs, C.

This plate has a centre-pin, D, which passes through the supporting-part of the hinge E, which is attached to the window-casing, and extends out therefrom sufficiently far to give the plate B room to revolve thereon outside of the window-casing.

There is also a lip or cover, F, extending down from the edge of the plate B below the cogs C, so as to protect them from snow, ice, and dust.

H is a bevel cog-wheel, firmly attached to the shaft I, that extends through the window-casing from the inside of the house, there being a knob, J, on the inner end of said shaft, by which it is turned, as hereafter described.

There is a toothed circular plate, K, firmly attached to the shaft I, just inside of the window-casing, and also a pawl, L, hung to the window-casing in such a position that it will swing down and engage with the teeth of the plate K, and hold the plate and its shaft I from turning, when desired.

The bevel-wheel H is so arranged that it engages with the cogs C on the under side of the circular plate B, so that, when the shaft I is turned, the plate B is revolved on its central pin D, and opens or closes the blind S.

The shaft I is turned by a person taking hold of the knob J, and when it has been turned, and the blind swung to the desired position, the pawl L is swung down so as to engage with the teeth of the plate K, and holds the shaft I from turning, and thereby locks the blind.

My hinge can be attached to any blind and window-casing, by simply boring a hole through the casing for the shaft I, and by the construction of the hinge with the large circular plate B, there is a leverage obtained which causes the blinds to be more easily swung.

By placing the cogs C on the under side of the plate B, and using the lip or cover F, the gearing of the hinge is so protected that it will keep clear of snow, ice, and dust, that would otherwise be apt to clog it, and interfere with its operating.

By using the shaft I and its attachment in connection with the hinge, the blind can be opened, or closed and locked, in any desired position, from the inside of the house, without opening the window.

Having thus fully described the construction and operation of my improved hinge,

What I claim, and desire to secure by Letters Patent, is—

When forming a part of a window-blind hinge, the circular plate B, when provided with a central pivoting-pin, D, cogs or teeth C, and lip or flange F, in combination with the support E and bevel-wheel H, when all are constructed and arranged substantially as and for the purposes specified.

TYLER C. LORD.
